US00D642584S

(12) **United States Design Patent**
Wong et al.

(10) **Patent No.:** **US D642,584 S**
(45) **Date of Patent:** **** Aug. 2, 2011**

(54) **USB STORAGE DEVICE**

(75) Inventors: **Kwok Fong Wong**, New Territories (CN); **Pui Yi Ching**, New Territories (CN)

(73) Assignee: **Shining Union Limited**, Tsuen Wan, New Territories, Hong Kong (CN)

(**) Term: **14 Years**

(21) Appl. No.: **29/364,886**

(22) Filed: **Jun. 30, 2010**

(30) **Foreign Application Priority Data**

Jan. 7, 2010 (HK) 1000028

(51) **LOC (9) Cl.** **14-02**

(52) **U.S. Cl.** **D14/480.4; D14/480.6**

(58) **Field of Classification Search** D14/411, D14/433, 435.1, 436, 480.1–480.7, 484.1, D14/137, 155, 203.1–203.8, 240; D3/201, D3/273; D13/107, 108, 133, 154, 184; 710/300, 710/301; 439/131, 135–147; 361/379.31, 361/679.33, 679.4, 752; 711/100, 115
